GRID LEAK

Filed June 29, 1926

FIG. 1.

FIG. 2.

Inventor

J. Connors.

By

John P. Dugan

Attorney

UNITED STATES PATENT OFFICE.

JAMES CONNERS, OF CRESCENT CITY, CALIFORNIA.

GRID LEAK.

Application filed June 29, 1926. Serial No. 119,339.

This invention relates to new and useful improvements in grid leaks used in connection with radio receiving sets, and consists in the novel features of construction, combination and arrangement of parts illustrated in the accompanying drawings and more particularly pointed out in the appended claim.

In the accompanying drawings, which are for illustrative purposes only and are therefore not drawn to scale:

Figure 1 is a side elevation of a grid leak constructed in accordance with my invention and Figure 2 is an enlarged central 15 longitudinal section of the device.

Referring to the drawings for a more particular description of my invention and in which drawings like parts are designated by like reference characters throughout the 20 several views, my device comprises a central cylinder 1 of glass or other non-conducting material and the hollow end caps 2 of suitable conducting material. The cylinder 1 contains a liquid solution A of mercury, distilled water and nitric acid, and the ends 25 of the cylinder are hermetically sealed by the caps 2 aforesaid, letter wax 3 being preferably used for this purpose. The caps 2 are preferably formed with cylindrical 30 flanged necks 4 which extend into the ends of the cylinder and spherical body portions 5 terminating in pointed outer ends 6. The liquid solution A preferably consists of about 28 to 30 drops of mercury and nitric acid and enough distilled water to cut acid 35 in order to avoid forming gas, although it

is obvious that the proportions may be varied, as desired, to give the best possible results. The cylinder 1 and end caps 2 may be of any desired dimensions best suited for 40 the purpose or to meet commercial requirements.

It has been found from experiments that this device sharpens the set, gives more signal strength and natural tone of all instruments that are broadcasted and also eliminates an overload to all vacuum tubes that are installed in a set and thereby gives wireless telegraphy signals clear and distinct and balances the set perfectly and properly by 50 passing the overload of signals through the dectum tube. The device also gives accurate control of regeneration.

From the foregoing description, taken in connection with the drawings, it is thought 55 that the construction, operation and advantages of my invention will be readily understood without requiring a more extended explanation.

Having described my invention, what I 60 claim as new and desire to secure by Letters Patent, is:

A grid leak comprising an elongated cylinder of non-conducting material containing a solution of mercury, nitric acid 65 and distilled water and hollow spherical caps of conducting material hermetically sealing the ends of the cylinder.

In testimony whereof he hereby affixes his signature.

JAMES CONNERS.
